UNITED STATES PATENT OFFICE

137,291

DESIGN FOR A BOMB EXTINGUISHING DEVICE

Ferdinand C. Buono, New York, N. Y.

Application September 2, 1942, Serial No. 108,105

Term of patent 14 years

To all whom it may concern:

Be it known that I, Ferdinand C. Buono, a citizen of the United States, residing at New York, in the county of New York and State of New York, have invented a new, original, and ornamental Design for a Bomb Extinguishing Device, of which the following is a specification, reference being had to the accompanying drawing, forming part thereof.

Figure 1 is a perspective view of a bomb ex-

tinguishing device showing my new design.

Figure 2 is a side elevational view.

Figure 3 is a top plan view.

Figure 4 is a bottom plan view.

Figure 5 is an end elevational view.

I claim:

The ornamental design for a bomb extinguishing device, as shown.

FERDINAND C. BUONO.
